UNITED STATES PATENT OFFICE.

HARRY H. PFLAUGER, OF ST. LOUIS, MISSOURI, ASSIGNOR TO COMMONWEALTH STEEL COMPANY, OF GRANITE CITY, ILLINOIS, A CORPORATION OF NEW JERSEY.

TRUCK PEDESTAL.

Application filed March 10, 1927. Serial No. 174,272.

My invention relates to railway rolling stock and consists in an improved truck pedestal structure.

The object of my invention is to provide a truck pedestal structure which is adapted to utilize either standard A. R. A. journal boxes or the anti-friction journal boxes which are being used to some extent and which are substantially wider than the A. R. A. boxes.

My invention enables the railroad company to change readily from one type of box to the other without applying new pedestals. This makes a substantial saving in material and labor if a change is to be made.

Where the truck structure is of the type in which the pedestals are integral with the wheel pieces or with the entire truck frame, the cost of the change in boxes will be only a small fraction of what it would be if new pedestals and wheel pieces or frame were required.

In my copending application, Serial Number 174,271, filed March 10, 1927, I describe and claim a pedestal structure having the same general object in view, but in which the change from a pedestal taking an A. R. A. box to a pedestal taking the larger anti-friction box is made by machining away a portion of the pedestal legs. In my present invention, such machining operations are eliminated and the pedestal may be changed from an anti-friction box pedestal to an A. R. A. box pedestal as readily as from an A. R. A. box pedestal to an anti-friction box pedestal which is not true of the structure of my copending application referred to.

In the accompanying drawings which illustrate a selected embodiment of my present invention—

Figure 1 is in part a side elevation of a six-wheel truck in which the journal is equipped with an anti-friction box, and in part a side elevation of the same truck showing the journal carrying an A. R. A. journal box.

Figures 2 and 3 are, respectively, section taken on lines 2—2 and 3—3 of Figure 1, but illustrating wear plate holding elements different from those shown in Figure 1.

Figure 4 is a side elevation of a separate pedestal casting.

Figure 5 is a side view of a single pedestal leg embodying the essential features of my invention.

Figure 6 is a section through a pedestal leg and illustrates a modified form of the filler block and pedestal.

The truck shown in Figure 1 includes the usual wheels 1, the axle journals 2 of which mount the journal boxes 3 and 4. The journal boxes carry ordinary equalizers 5 which support the truck frame wheel pieces 6 through springs 7 in the usual manner. The truck frame illustrated is of the one-piece casting type in which the pedestals are formed integrally with the wheel pieces, but obviously my invention is not limited to application to this type of truck frame having integral pedestals.

The legs 8 of each pedestal are spaced far enough from each other to accommodate between them the wide anti-friction box 4 in substantially the same manner as such boxes are accommodated in ordinary pedestals now provided therefor. Each pedestal leg 8, however, is adapted to mount a filler block 9 which then practically forms a part of the pedestal leg. The blocks on adjacent pedestal legs reduce the distance between the journal box engaging faces to such an extent that the ordinary A. R. A. journal box may be assembled with the pedestal in proper operative relation.

Preferably, the blocks 9 are partly channel-shaped in cross section and partly of hollow rectangular cross section and may be riveted or bolted to the pedestal leg. The sides of the blocks have lips 11 and the pedestal legs 8 are recessed adjacent the transverse webs as indicated at 10 to receive the lips 11 of the blocks 9. Such an arrangement enables me to use the same wear plates 12 on the pedestal legs in either adaptation of the latter. These wear plates may be spot-welded to the pedestal leg as indicated at W in Figure 1 or may be secured thereto by bolts 13 as detailed in Figures 2 and 3.

Obviously it is a comparatively simple matter to either apply the filler blocks 9 to the pedestal leg or remove the blocks from the leg. Hence, the journal boxes may be changed from the A. R. A. type to the anti-friction type, or vice versa, at a minimum expense and without replacing any of the other truck parts.

The pedestal structure shown in Figure 4 resembles the ordinary pedestal in being adapted to be secured through its flange 14.

to the wheel piece of a truck frame, but corresponds to the pedestals shown in Figures 1, 2 and 3 in having its legs 15 adapted to mount filler blocks 16 and to have a wear plate 17 secured to it over the filler block or over the face 18 of the leg proper.

The leg structure illustrated in Figure 5 is substantially one-half of the complete pedestal shown in Figure 4 and is adapted to be mounted on the wheel piece independently of the cooperating leg. It also includes a flange 19 for attaching the same to the truck frame and a channel-shaped leg 20 adapted to mount the correspondingly shaped filler block 21 and, if desired, the wear plate 22.

Figure 6 illustrates a variation in the pedestal and block assembly. In this construction, the block 23 has a central lip 24 and the pedestal leg has a corresponding recess for this lip. These elements accurately position the block on the pedestal leg and resist the thrusts of the box due to the back and forth play of the axle and wheel. The wear plate 25 is shown as welded to the pedestal leg.

It is apparent that the details of the application of the filler blocks to the pedestal legs may be otherwise modified, and other variations in the pedestal structure may be made without departing from the spirit of my invention, and I contemplate the exclusive use of all the features of my invention as are included in the scope of my claims.

35 I claim:

1. A car truck pedestal leg having side walls and a transverse web between said side walls, said side walls being provided with spaced bolt holes for securing a wear plate 40 in different positions relative to said web.

2. In combination, a car truck pedestal leg, having a smooth face adapted to guide a vertically movable journal box mounted in the pedestal, and a block detachably secured to the inner face of said leg and having a smooth face adapted to similarly guide a narrower journal box mounted in the pedestal.

3. In combination, a car truck pedestal 50 leg comprising side walls, a transverse web between said walls, a filler block in front of said web and detachably secured to said walls, and a wear plate extending over said block and also secured to said walls.

55 4. In a car truck pedestal leg, side walls, a transverse web between said walls, a detachable filler block fitting over said web and the adjacent portion of said walls, and a channel-shaped wear plate fitting over said block and walls, said walls having holes for receiving means securing said block and wear plate to said walls, and said walls also having holes for receiving means securing

said wear plate when said block is detached and the wear plate is moved rearwardly to fit over said leg.

5. In combination, a truck pedestal having spaced legs adapted to receive and properly engage an anti-friction bearing journal box between them, and detachable means between the opposing faces of said legs whereby a standard A. R. A. journal box may be positioned in said pedestal.

6. In combination, a truck pedestal having spaced legs adapted to receive and properly engage an anti-friction bearing journal box between them, and a detachable member on each of said legs adapting the latter to engage the sides of an A. R. A. journal box.

7. In combination, a truck pedestal having spaced legs adapted to receive an anti-friction bearing journal box between them, and a detachable member on each of said legs adapting the latter to engage the sides of an A. R. A. journal box, and wear plates 80 adapted to fit over said members or fit over said legs when said members are detached.

8. A truck frame with an integral pedestal having spaced legs, filler blocks detachably secured to said legs, there being room 90 between said blocks for a journal box of a given width, and there being room between said legs, when said blocks are detached, for a journal box of substantially greater width.

9. A car truck pedestal leg having side 95 walls provided with spaced bolt holes for securing a wear plate in different positions relative to said walls.

10. In combination, a car truck pedestal leg, a filler block on the inner face of said leg and detachably secured thereto, and a wear plate extending over said block and also secured to said leg.

11. In combination, a truck pedestal having spaced legs adapted to receive and properly position an anti-friction bearing journal box between them, a detachable member on each of said legs adapting the latter to properly position an A. R. A. journal box, and wear plates adapted to be positioned over 105 said members or over said legs when said members are detached.

12. A truck frame with an integral pedestal having spaced legs, filler blocks detachably secured to said legs, there being room 115 between said blocks for a journal box of a given width, and there being room between said legs when said blocks are detached for a journal box of substantially greater width, and wear plates applicable to said legs 120 whether said filler blocks are assembled therewith or not.

In testimony whereof I hereunto affix my signature this 7th day of March, 1927.

H. M. PFLAGER.
